UNITED STATES PATENT OFFICE

129,904

DESIGN FOR A SHEET OR SIMILAR ARTICLE

Vera Way Marghab, New York, N. Y.

Application May 25, 1940, Serial No. 92,597

Term of patent 14 years

To all whom it may concern:

Be it known that I, Vera Way Marghab, a citizen of the United States, residing at New York, county and State of New York, have invented a new, original, and ornamental Design for a Sheet or Similar Article, of which the following is a specification, reference being had to the accompanying drawings, forming part thereof, wherein—

of a bed sheet or similar article showing my new design, the remainder of the sheet being plain as indicated by the ruled outline, and

Fig. 2 is an enlarged fragmentary view of the upper portion of the sheet shown in full lines in Fig. 1.

I claim:

The ornamental design for a sheet or similar article, substantially as shown and described.

VERA WAY MARGHAB.
